DESIGN FOR A DRESS

Louis L. Kashine, New York, N. Y.

Application August 27, 1940, Serial No. 94,652

Term of patent 3½ years

To all whom it may concern:

Be it known that I, Louis L. Kashine, a citizen of the United States, residing in New York city, in the county of Manhattan and State of New York, have invented a new, original, and ornamental Design for a Dress, of which the following is a specification, reference being had to the accompanying drawing, forming part thereof.

Fig. 1 is a front view of a dress showing my design, and

Fig. 2 is the rear view thereof.

The characteristic feature of my design resides in the combination on the dress disclosed of the specific, rounded waistyoke having cartridge tucks extending completely across the top of the curve, in association with the cartridge pleats below the shoulder yokes, and the pleated skirt panel extending into the waistyoke, all as shown.

I claim:

The ornamental design for a dress, substantially as shown and described.

LOUIS L. KASHINE.
